UNITED STATES PATENT OFFICE.

EDWARD M. GROSS AND FRED E. MAYES, OF LOUISVILLE, KENTUCKY.

COMBINATION ELECTRIC SWITCH.

Application filed July 14, 1920. Serial No. 396,102.

To all whom it may concern:

Be it known that we, EDWARD M. GROSS and FRED E. MAYES, citizens of the United States, residing at Louisville, in the county of Jefferson and State of Kentucky, have invented certain new and useful Improvements in a Combination Electric Switch, of which the following is a specification.

This invention relates to a combination electric switch which is more particularly designed for use in connection with automobiles or other vehicles or machines which depend for their operation upon the closing of the electric circuits and the purpose of 10 this invention is to provide a switch of this character which is simple and inexpensive in construction, easily operated and capable of being readily shifted into such a position that the desired electric circuits are closed 15 and also shifted into such a position that these circuits are open and cannot ordinarily be closed by any person other than one familiar with the particular combination of the switch.

Another object of the invention is to provide a plurality of switches corresponding to the number of cylinders of the internal combustion engine, these switches being disposed between the spark plugs thereof and the timer so that it will be necessary to set 20 each switch in its proper position before the engine may be started.

With these and other objects in view, the invention consists in the novel construction, combination and arrangements of parts herein illustrated and more specifically pointed out in the appended claim.

In the accompanying drawing:—

Figure 1 is a front elevation of our invention,

Figure 2 is a section taken on the line 2—2 of Fig. 1,

Figure 3 is a section taken on the line 45 3—3 of Fig. 2 and showing the circuits diagrammatical,

Figure 4 is a section taken on the line 4—4 of Fig. 3 looking in the direction of the arrow, a.

Referring to the corresponding parts of the several views by the same numerals of reference, 1 denotes the support upon which is mounted the switch plate 2. A casing 3 is situated over the switch plate 2 and has a

plurality of longitudinally spaced openings in its front wall. A plurality of ratchet

plates 4 having the toothed collars 5 longitudinally disposed along the center of the switch plates are arranged so as to register with the openings in the casing 3. Insulating flanged washers 6 are situated within the openings in the casing 3 for rotatably receiving the shafts 7 which extend into the collars 5 of the ratchet plates 4. A pair of circuit closing arms radially and laterally 60 extend from each of the shafts 7 a spaced distance from the inner ends thereof. An expansion coil spring is disposed around each shaft and bears against the flanged washers 6 and the circuit closing arms. Between the circuit closing arms and the collar 5 there is fixedly attached to the shaft a toothed ferrule 9 and thus it will be seen that the spring 8 will normally hold the toothed ferrule 9 and toothed collar 5 in engagement with each other as shown to advantage in Figure 4.

The switch plate 2 is provided with a plurality of openings arranged in two rows at the top and bottom and so as to be between and above and below the ratchet plates 4 as is clearly shown in Figure 3. Insulating sleeves 10 are situated in these openings to receive the tubes 11 having the threaded stems 12. Contact plates are disposed on the stems between the lock nuts 13. In Figure 2 of the drawing it will be seen that the shaft 7 is provided with the rubber knob 7' upon the outer face of which is provided a dial 40 having numbers arranged in a clock-wise direction from zero to five. As shown in Figure 1 of the drawing the switches are all arranged so that the engine may be started and continue to run. When in this position by referring to Figure 3 of the drawing it will be seen that the contact arms 24 close the circuit between the contact plates 14 and 19 upon the first shaft 7, the contact arms 24 upon the second shaft 7 closes the circuit between the contact plates 15 and 21, the circuit closing arms 24 upon the third shaft 7 close the circuit between the contact plates 16 and 17, and the circuit closing arms 24 on the fourth shaft 100 close the circuit between the contact plates 18 and 22 and it will be noted that the contact plates 20 and 23 are of no use except to act as a decoy to anyone tampering with the device.

By referring to Figure 3 of the drawing 110 it will be seen that the magneto 25 has one terminal grounded at 37 while the wire 41

carries the current to the timer 26. The current then passes from the timer 26 through the wire 27 to the contact plate 14 through the arms 24 to the contact plate 19. 5 From here the current passes through the wire 28 to the spark plug upon the first cylinder, thence through the wire 38 to the ground 37. When this circuit is broken by the timer the next circuit is formed and the 10 current passes from the timer 26 to the wire 29 to the plate 15, through the arms 24, to the plate 21. From here it passes through the wire 30 to the spark plug upon the third cylinder and thence through the wire 38 to the 15 ground 37. When this circuit is broken the next circuit is formed and the current passes from the timer 26 through the wire 31 to the contact plate 17, through the arms 24, to the plate 16. From here the current 20 passes through the wire 32 to the spark plug 36 upon the fourth cylinder and thence through the wire 38 to the ground 37. When this circuit is broken and the next circuit formed it consists of the current 25 passing from the timer 26 through the wire 33 to the plate 22, through the arms 24 to the plate 18 thence through the wire 34 to the spark plug 36 upon the second cylinder and thence through the wire 38 to the 30 ground 37 and of course this process continues in a well known manner.

When it is desired to stop the engine all that will be necessary is to turn the knob 7' thus breaking the circuits through the necessary contact plates and of course no unauthorized person not knowing the combination will be able to properly set the switches in order to start.

From the foregoing description, taken in

connection with the accompanying drawing, 40 the construction and operation of the device will be readily understood without a more extended explanation. As numerous changes in form, proportion, and in the minor details of construction may be resorted to 45 without departing from the spirit of this invention, we do not wish to be limited to the construction herein shown and described other than as claimed.

Having thus described our invention what 50 we claim as new is:—

As a new article of manufacture, a combination electric switch for ignition circuits, comprising a casing including a front and a rear wall, a bearing collar secured to the rear wall formed of non-electric conducting material having an annular row of teeth formed thereon, a rotatable shaft carried by the front wall and having its inner ends rotatably mounted in said collar, a toothed 60 ferrule secured to the shaft for engaging the teeth of the collar, a pair of spaced contacts secured to the rear wall and arranged in radial spaced relation to the shaft and collar, radially extending arms secured to 65 the shaft for wiping contact with said spaced contacts and a spring coiled about said shaft engaging the radially extending arms and the inner surface of the front wall.

In testimony whereof we affix our signatures in presence of two witnesses.

EDWARD M. GROSS.
FRED E. MAYES.
